COMBINED TIE RACK AND PICTURE FRAME

Emanuel G. Steib, Forest Hills, N. Y.

Application April 1, 1950, Serial No. 8,903

Term of patent 7 years

(Cl. D33—8)

To all whom it may concern:

Be it known, that I, Emanuel G. Steib, a citizen of the United States, residing in Forest Hills, in the county of Queens, city and State of New York, have invented a new, original, and ornamental Design for a Combined Tie Rack and Picture Frame, of which the following is a specification, reference being had to the accompanying drawing, forming a part hereof, in which:

Fig. 1 is a front elevation of a combined tie rack and picture frame embodying my new design.

Fig. 2 is an end elevation thereof.

Fig. 3 is a top plan view thereof.

Fig. 4 is a broken perspective view of one end of the article.

Fig. 5 is a broken perspective view of the central section of the article.

I claim:

The ornamental design for a combined tie rack and picture frame, as shown.

EMANUEL G. STEIB.
